4 Claims. (Cl. 141—105)

This invention relates to fluid dispensing apparatus and involves a novel arrangement for proportioning, mixing and dispensing a plurality of fluids, under pressure, through a common outlet, by unidirectional lever action. In particular, the present invention is adapted for the proportioning, mixing and dispensing of soft drink concentrates with a soda water base.

Among the requirements for apparatus of this character are accuracy of proportioning; simplicity of installation and operation; cleanliness; minimum agitation of the soda water; attractive appearance; and low cost.

The present invention satisfies these requirements in that it may be operated simply by pressing a glass, which is to receive the drink, against a lever actuator, and holding it in that position until the glass is filled. Accurate proportioning and the dispensing of the fluid mixture is accomplished by a novel arrangement of a pair of valves which, with their actuators, are designed with such capacities as to proportion properly the concentrate and the soda water diluent with a minimum agitation whenever my novel means, which actuates both valves simultaneously, is operated.

The lever actuator may be provided with means, such as a pair of diverging fingers, for receiving the glass. The two fluids are mixed and delivered through a common fixed spout, the mouth of which is disposed directly above the glass when so inserted in such receiving means. This spout may protrude through an orifice or slotting in the actuator lever which is so constructed as to be movable relative to the spout.

In one embodiment of the invention, the proportioning of the liquids is actually accomplished by a pair of plungers disposed in barrels in the wall behind the lever actuator, these plungers being directed in line with the movement of the lever actuator so as to be pushed by the latter in the course of its stroke. The end of each plunger most removed from the actuator may be fluted or serrated from its outer wall radially inwardly. The thus-serrated tip of the plunger is maintained in contact with a ball valve, spring-biased to close a coaxial O-ring valve port of a coaxial cylindrical chamber. A duct leading from each chamber is connected to the source of one of the two fluids to be mixed. The wall of each barrel surrounding the serrated end of its plunger is opened or connected by duct means to the common outlet which terminates in the spout through which the mixed fluids, are delivered to the glass. Pressure exerted by the lever actuator simultaneously against both plungers results, in the case of each valve, in unseating the ball from the O-ring valve port, thereby permitting fluid in the chamber to pass from the valve chamber along the fluting or serrations with a minimum agitation and into the common outlet.

In another embodiment, valving of each fluid is accomplished by providing a chamber, the inside diameter of the walls defining such chamber being increased for a distance from a preselected point in the barrel in which an actuating plunger is slidably inserted. A ball-like

2

valve member is spring-biased to close off the chamber from the barrel, but this member yields to provide an open passage therethrough when force is exerted by the plunger and on the valve member in an axial direction opposite that of the spring.

Determination of the proportions of the fluids to be delivered for mixing during each dispensing is accomplished in part by providing valve ports and/or ducts of preselected diameter for each of the two fluids. Thus, 10 the valve port for the concentrate may be constructed of a diameter substantially less than the diameter of the valve port through which the soda water is to be passed to the common outlet.

Adjustment of the proportioning may be accomplished 15 by providing means for varying the stroke of the plungers with any given movement of the lever actuator. The preferred means for effecting such variance comprises a pair of screws disposed in, and extending through, the actuator, and aligned coaxially with the plungers. These 20 screws may be threaded through the actuator to contact the ends of the plungers, and thereby increase the strokes thereof for any given movement of the lever actuator.

It is also possible with this novel apparatus to effect 25 a selection of the fluids and quantities thereof for each particular dispensing. This may be accomplished by disposing one of the two valve actuating plungers in such a manner that it is not actually contacted during initial movement of the lever, while the other plunger is disposed to abut the lever at its non-actuating position. With this 30 arrangement, when the lever actuator is only partly pressed, fluid is delivered to the common outlet from the single valve which is actuated. The second fluid is not added then until the lever is pressed further and contact is made with the second plunger. In the particular embodiments of the invention, which is herein illustrated and described, this would permit the operator to increase the strength of the drink by permitting only concentrate to flow into the glass during part of the dispensing operation.

The manner in which the apparatus is constructed and 40 operates may be further understood from the description thereof which follows with reference to the accompanying drawings, in which

Figure 1 is a perspective view of part of a battery of several units of the apparatus set up to dispense mixed drinks at a soda fountain;

Figure 2 is a section taken along the line 2—2 of Figure 1;

Figure 3 is a partial view similar to that of Figure 2, but showing the disposition of the components of the apparatus when the actuating lever is depressed;

Figure 4 is a perspective view of an alternative means 50 for pivotably attaching the lever actuator to the forward wall of the dispenser blocks;

Figure 5 is a section taken on the line 5—5 of Figure 4;

Figure 6 is a partial section similar to the upper portion of Figure 2, showing an alternative valving arrangement for use in the apparatus; and

Figure 7 is an exploded elevation, partly in section, 60 of the plunger and valve assembly employed in the Figure 6 embodiment.

The apparatus, illustrated in Figures 1 through 3, comprises a plastic body 10 which is adapted to be bolted to a suitable shelf 12 of a soda fountain or other place from which the drinks are to be dispensed. A horizontal bore 14 is drilled through the rear portion of this body 10, and this bore 14 is appropriately connected by means 16 to a pipe 18. The latter leads to the source (not shown) of a liquid, such as soda water, which is to be mixed with the concentrate to dilute the same into a palatable drink. Below the level of the duct 14 in the body 10, are bores 70 20, each of which is widened toward the rear of the housing at 22 to receive the nipple 24 of a concentrate

duct outlet 26. Above and parallel to each of the bores 20, another bore 28 is drilled to connect with the horizontal bore 14. A counterbore 30 is provided to extend from each bore 20, through to the forward wall of the body 10. Similarly, a counterbore 32 is provided to connect with each bore 28. Each of these counterbores 30 and 32, where it meets its respective bore 20 or 28 respectively, forms an annular rim 34, 36, respectively, against which may be seated, in the case of counterbore 30, a helical spring 38; and in the case of the counterbore 32, a similar spring 40.

The body 10 is further bored at an angle from its underside 42 to provide a passage 44, and into the lowermost extremity of this bore 44, a sleeve-like member 46 is inserted to serve as a spout. The bore 44 is located to intersect both counterbores 30 and 32. At an appropriate point rearward of the intersection of the bore 44 with each of the bores 30 and 32, is provided, in the wall defining the counterbore 32, an annular groove 48 in which is disposed an O-ring 50. Similarly, in the wall defining the counterbore 30, is provided a pair of annular grooves 52, 54 which serve to receive O-rings 56 and 58 respectively. A ball valve member 60 is seated against the O-ring 50; and similarly, a ball valve member 62 is seated against the O-ring member 56. The spring 40 serves to pass the ball 60 against the O-ring 50, and, in like manner, the spring 38 serves to press the ball 62 against the O-ring 56, to prevent the passage of fluid past these ball valve members.

Actuation of the valve members 60 and 62 is effected by a pair of plungers 64, 66 respectively. Each of these plungers is cylindrical in shape and is inserted in that portion of its counterbore forward of the ball valve, but with one end pressing against the latter. The circumference of the inner end of each of the plungers 64 and 66 is cut to provide a series of axially extending serrations or flutings 68.

Appropriate sealing means 70 and 72 are provided forward of the intersection of the bore 44 with the counterbores 30 and 32, to prevent the passage of any fluid along the plungers to the forward end of these counterbores. Each of the plungers 64 and 66 is made long enough to extend from its respective ball valve 60, 62 to a point just outside of the forward wall 74 of the body 10. In the preferred embodiment of the invention, the two counterbores 30 and 32 are aligned with their axes in a common vertical plane so that the axes of the two vertical plungers are correspondingly aligned. On the upper portion of the forward wall 74 of the body 10, a bracket 76 is provided which serves to mount pivotally, by means of a pin 78, a lever actuator 80.

This actuator 80 is formed with an upper vertical portion 82, a rearwardly extending segment 84, angled back from the portion 82, and a lower vertical extending portion 86 which may be integrally formed with a pair of forwardly diverging fingers 88. On these fingers 88, preferably are provided balls 90 of resilient material, such as rubber, thereby to adapt the two fingers to receive for pressing engagement a glass or other container (not shown) in a manner commonly found in a cafeteria or soda fountain water dispensers. The central area of the segment 84 and upper part of the portion 86 are cut out to permit the spout 46 to extend downwardly through the member 80, and to allow movement of the latter relative to the spout about the pivot axis 78.

The body 10 is further bored at 92 to provide a duct extending between the serrated end of the plunger 66 and bore 44.

The actuator 80 is further bored in the axes of the counterbores 30 and 32, at 94 and 96 respectively, and these bores 94 and 96 are threaded to receive screws 98 and 100 respectively, the function of which will be described hereinafter.

The apparatus operates simply in the following manner:

Fluid from the source of concentrate enters the cham-

ber 31, which is formed rearward of the ball check valve 62 in the counterbore 30, via pipe 26, nipple 24 and bore 20. The diluent fluid, such as soda water, which is to be mixed with the particular concentrate, arrives from its source through the pipe 18, duct 14 and bore 28 in the chamber 29, formed by the portion of the counterbore 32 rearward of the ball check valve 60. Both valves 60 and 62 are normally biased to closed position by the respective springs 40 and 38. It will be seen, however, that the application of any substantial horizontal force against the plungers 64 and 66 will result in the unseating of the ball valve members 60 and 62, thereby permitting fluid under pressure in the chambers 29 and 31 to pass around the ball, and along the series of flutings or their respective serrations 68. In the case of the plunger 64, fluid passing the ball valve member 60 and along the serrations 68, escapes directly into the bore 44 through which the fluid flows downwardly and out of the spout member 46. In the case of the plunger 66, it will be seen that the fluid, which passes the ball 62, flows along the fluted end of the plunger 66 and down through the duct 92 to enter the bore 44 from whence it also passes downwardly and out through the spout 46.

The exertion of the requisite horizontal forces in the axes of the two plungers 64 and 66 is accomplished by pressing the lever actuator 80 inwardly toward the wall 102 of the fountain in the manner illustrated particularly in Figure 3. Such pressure causes the actuator 80 to pivot slightly about the axis pin 78. Since the upper portion 82 of the actuator 80 is normally maintained either in contact, or almost in contact with the forwardly projecting ends of the plungers 64 and 66, pivoting the member 80 rearwardly applies a rearwardly directed horizontal pressure against both the projecting ends of these two plungers. The screws 98 and 100 may be advanced to vary the stroke of the plungers 64 and 66, thereby permitting some adjustment to be made in the quantity of fluid which is passed by each of the valve members 64 and 66. Thus, if it is desired to increase the amount of concentrate which is permitted to pass by the check valve 62, the screw 98 may be turned to pass through the member 80 so that its extremity abuts the end of the plunger 66 when the actuator 80 is in non-actuation position. In this posture, depressing the lever 80 rearwardly will cause the plunger 66 to unseat the ball 62 from the ring 56 and force it back the farthest distance, thereby permitting the greatest quantity of concentrate to pass through the valve for dispensing. Conversely, if the screw 100 is threaded inwardly to make contact with the forward projecting end of the plunger 64 in the non-actuating position of lever 80, then rearward movement of the actuator 80 will first unseat the ball valve 60 from the O-ring 50 and force it back the farthest distance, thereby to allow the greatest quantity of water, soda or other diluent to flow past the ball 60 and enter the bore 44 for mixing and delivery through the spout 46 into the glass held therebelow.

It is also possible to adjust my dispensing apparatus in such a manner that the operator may have the option of dispensing in the glass only concentrate to increase the strength of the drink. Where it is desired to accord this option to the operator, the plunger 64 may be made of such length that its unserrated end does not initially abut the back of the actuator 80 when the latter is in its non-actuating position. The length of the plunger 66, however, would be made such as to have its end in abutment with the back of the lever 80. With such designing of the two plungers, it will be appreciated that, during the initial part of the movement of the lever 80 rearwardly toward the wall of the fountain 102, only the valve 62 will be unseated from its O-ring 56 to pass concentrate from the chamber 30 to the bore 44 and spout 46. After the lever 80 is depressed as far as it will go toward the wall 102, contact is then made with the second plunger 64 to allow both fluids to flow into the bore 44

for mixing and dispensing. If it is desired to provide the operator with an option of running soda water alone, then obviously the plunger 64 will be made long enough to abut the member 80 and the plunger 66 will be shortened to avoid contact during initial movement of the lever 80. Alternatively, both plungers may be shortened enough to avoid initial contact with the back of the lever 80 and initial contact may be made by threading in one or the other of the two screws 98 and 100.

Figures 4 and 5 illustrate an alternative method of pivotally securing the actuator lever 80 to the wall 74. In this embodiment, which is actually preferred over the more standard construction shown in Figures 1-3, two ball-headed bolts 110 are embedded in the body 10 and secured against lateral movement in said body by nuts 112. The lever actuator 80 is then constructed of a plastic block 114 into which are further embedded two vertical members 116, 118. The latter are bent back and bridged to form a handle structure generally similar to that shown in the Figures 1-3 embodiment. The block 114 is drilled on its back side to provide a pair of bores 120 to receive the ball heads 122 of the bolts 110. Each bore 120 is cut out at 124 specially to receive the ball head as shown in Figure 5, and is further cut to provide an annular circumferential channel 126. A small O-ring 128 having only a very slightly larger outside diameter than the bore 120 is then inserted and pressed into the end of the bore, where it is secured by a larger O-ring 130, seated in the channel 126. The ball end 122 of each bolt 110 may then be pressed into the bore 120 past the two O-rings and into the spherical cavity 124. The block 114 is thus held close to the wall 74, but is permitted by the arrangement of the ball-headed bolts 110 in the double O-ring lined bore 120 to be pivoted vertically a sufficient distance to actuate the plungers 64 and 66. Advantageously, the entire actuator 80a may be removed, by simply pulling the block away from the wall 74 along the axis of the bolts 110.

The valve embodiment of Figures 6 and 7 may be preferred for installations where the nature of the fluids proportioned and dispensed is such that they may tend undesirably to deposit and stick in O-ring grooves which may be cut at points along the flow passage. To eliminate such grooves, the walls of the counterbores 30, 32 are reamed at 30a, 32a respectively to provide bulb-like cavities 30b, 32b which serve as valve chambers. Valving of the fluids may be accomplished by the plunger assembly shown in Figure 7, which assembly comprises a sleeve 140, having inner threading, a matingly threaded bolt 142, one end of which is provided with a coaxial portion 144 of lesser diameter than that of the threaded portion, and a head 146 backed by a node 148. A donut shaped resilient O-ring or washer 150 is slipped over the threaded end of the bolt until it is seated on the portion of lesser diameter and against the head 146. The sleeve 140, which may be of plastic, is formed with a lesser outside diameter than the inside diameter of the counterbores 30, 32.

To install this valve assembly the sleeve 140 is threaded partway onto the bolt 142, leaving the O-ring 150 free to expand axially between the end 152 of the sleeve and the head 146 of the bolt 142, and the entire assembly is then slipped into the counterbore 30, or 32 from the front wall 74 until the node 148 seats in the spring 38 or 40 and the O-ring 150 and head 146 are disposed in the bulb-like chamber 30b or 32b. Despite the fact that the outside diameter of the ring 150 is larger than the inside diameter of the counterbores 30, 32, the assembly may be forced through these counterbores because the ring 150 can distort axially along the portion 114 of the bolt 142. After the ring reaches the chamber 30b, however, it expands radially to its normal shape. A screw driver is then inserted into the slot 156 through the end 154 of the sleeve 140 and the bolt 142 is screwed back

into the sleeve 140 until the end 152 presses tightly against the side 158 of the O-ring 150, and squeezes the latter against the bolt head 146. This squeezing of the ring 150 causes it to expand radially, and when biased by the spring 38 or 40, serves to close the chamber 30b or 32b from the counterbore 30 or 32 respectively. Upon the application of horizontal pressure to the end 154 of the sleeve, the squashed ring 150 valve closure is unseated and moved into the center of the chamber 30b or 32b, allowing fluid under pressure in the chamber to pass around the ring and into the counterbore along the outside of the sleeve 140 until it reaches either passage 44a directly or 92a, from whence it proceeds for mixing and dispensing in a manner similar that of the Figures 1-3 embodiment.

O-rings 158 are provided to prevent fluid from passing in the counterbores 30, 32 along the sleeves 140 into undesired areas.

Further, in the Figures 6 and 7 embodiment, is shown an annular restrictor element 160 which is integrally formed with the end of each of the springs 38a, 40a. This restrictor element 160 is frusto-conically shaped at its free end to seat in the mouth of the bores 20, 28, and is itself bored in its axis at 162 to provide a passage from bores 20a and 28a to counterbores 30 and 32 respectively. These restrictors thereby serve to limit the volume of fluid which is permitted to pass through the respective valve arrangements.

From a consideration of the accompanying drawings 30 and the foregoing disclosure, it may be seen that the apparatus of this invention can be utilized to provide definite proportioning of two liquids, or to provide such proportioning with an option to the operator to dispense singly one or the other of the two constituent fluids.

It will also be appreciated that the apparatus is simple and economical in construction and may be added to conventional soda fountain installations without substantial modification of existing structures.

While certain particular valve arrangements have been illustrated and described, it will be obvious to anyone skilled in the art that many variations may be made in the actual valve structure employed, which variations will utilize the principles of construction and operation herein disclosed. All such modifications are intended to be comprehended within the scope of the invention hereinafter claimed.

I claim:

1. Apparatus for dispensing an admixture of a plurality of liquids into an open top container, said apparatus comprising a valve body, said valve body having a front face and a block of material extending rearwardly therefrom; a pair of chambers in said valve body; a pair of first duct means also in said valve body, each of said means connecting one of said chambers to a separate source of fluid under pressure, and each said chamber being provided with an outlet valve port and valve means for opening and closing said valve port, each said valve means being spring urged forwardly to closed position; a pair of duct passages in said valve body, each of said passages extending forwardly from one of said ports in a straight axis; said pair of valve chambers, outlet ports, valve means and duct passages, being so arranged as to dispose one said port, one said valve means and one said passage above another with their respective axes lying in a substantially vertical common plane; a dispensing spout, said spout extending downwardly from a level at least as low as that of the lowermost of said passages; second duct means communicatively connecting both of said passages with said spout; a pair of valve means actuating stem elements, one of each of said elements being of substantially lesser outside diameter than the inside diameter of, and disposed coaxially and slideably in, one of said passages, and extending forwardly past said second duct means to project one of its extremities from the front face of said valve body; and a lever

actuator, said actuator being pivotally mounted on the front face of said valve body to pivot in said plane and with its pivot axis disposed above the uppermost projecting stem extremity, and said actuator extending downwardly in said plane below the spot outlet; said actuator thereby being adapted to contact and apply a rearwardly directed force to both said stem element extremities; said actuator being orificed to permit the spout to project therethrough, and said spout being directed so to project through said orifice; whereby when the rim of the container is pressed rearwardly against the actuator at a point below the level of the spout, the actuator causes the valve stem elements to open the pair of valve means thereby to pass via the passages, fluid from both chambers into the spout, and thence to the container.

2. The apparatus as described in claim 1, wherein the spout extends downwardly through the underside of the block of material adjacent the front face thereof, and the lever actuator is bent back rearwardly toward the underside of said block and thence downwardly substantially normally thereto, the orifice in the actuator being provided in the bent portion of the leved actuator to permit the spout to project therethrough.

3. In a dispenser comprising a valve body having a front face and a block of material extending rearwardly therefrom, a bulbshaped chamber in said valve body, a cylindrical bore in said valve body, said bore being of lesser diameter than the maximum diameter of said chamber but being coaxial therewith, a dispensing outlet, said bore being communicatively connected with said dispensing outlet, said chamber being communicatively connected with a source of fluid under pressure to be dispensed, and a bore extension, said bore extension projecting rearwardly from and coaxially with said chamber and having an annular area remote from said chamber extending radially inwardly to receive one end of a coil spring; valve means comprising a cylindrical stem of substantially lesser outside diameter than the inside diameter of said bore, said valve stem being provided with an annular shoulder extending radially outward and disposed adjacent but spaced from the inwardly extending extremity of said stem, the opposite extremity of said stem being recessed to receive a screw driver tip and said stem further being threaded along at least a portion of its length from the last said extremity, a resilient bulblike element disposed coaxially on said stem in abutment with said shoulder, said bulblike element, when placed on said stem being slightly greater in maximum diameter than the inner diameter of the bore, a sleeve on said stem, said sleeve also being of an outside diameter less than the inside diameter of the bore so as to permit the passage of fluid between the outer walls of said sleeve and the bore walls, said sleeve being provided with inner threading cooperating with the threading on said stem, said sleeve being annularly recessed to receive an O-ring adjacent to but spaced from its forward extremity, and a coil spring, one end of said spring receiving the rear extremity of said stem and abutting said shoulder, and the other end being received in said annular area, whereby said spring and said stem may be inserted in said bore to dispose said bulblike element in said chamber and the stem tightened within said sleeve

5 to compress said bulblike element axially to cause it to expand radially and thereby form in said chamber a valve normally closed by the urging of said spring, but adapted to open upon the application of an axial force rearwardly applied to the forward extremity of said stem.

4. In a dispenser comprising a valve body having a front face and a block of material extending rearwardly therefrom, a bulb-shaped chamber in said valve body, a cylindrical bore in said valve body, said bore being of 10 lesser diameter than the maximum diameter of said chamber but being coaxial therewith, a dispensing outlet, said bore being communicatively connected with said dispensing outlet, said chamber being communicatively connected with a source of fluid under pressure to be dispensed, and a bore extension, said bore extension projecting rearwardly from and coaxially with said chamber and having an annular area remote from said chamber extending radially inwardly to receive one end of a coil spring; valve means comprising a cylindrical stem of substantially 15 lesser outside diameter than the inside diameter of said bore, said valve stem being provided with an annular shoulder extending radially outward and disposed adjacent but spaced from the inwardly extending extremity of said stem, said stem further having a portion of lesser diameter than the remainder of the stem, said portion extending forwardly from said shoulder, the opposite extremity of said stem being recessed to receive a screw driver tip and said stem further being threaded along at least a portion of its length from the last said extremity, a resilient bulblike element disposed coaxially 20 on said stem in abutment with said shoulder, said bulblike element, when placed on said stem being slightly greater in maximum diameter than the inner diameter of the bore, a sleeve on said stem, said sleeve also being of an outside diameter less than the inside diameter of the bore so as to permit the passage of fluid between the outer walls of said sleeve and the bore walls, said sleeve being provided with inner threading cooperating with the 25 threading on said stem, said sleeve being annularly recessed to receive an O-ring adjacent to but spaced from its forward extremity, and a coil spring, one end of said spring receiving the rear extremity of said stem and abutting said shoulder, and the other end being received in said annular area, whereby said spring and said stem 30 may be inserted in said bore to dispose said bulblike element in said chamber and the stem tightened within said sleeve to compress said bulblike element axially to cause it to expand radially and thereby form in said chamber a valve normally closed by the urging of said spring, but adapted to open upon the application of an axial force rearwardly applied to the forward extremity 35 of said stem.
